UNITED STATES PATENT OFFICE.

HENRY H. VAUGHAN, OF MONTREAL, QUEBEC, CANADA.

HEAD-GEAR.

1,238,966.

Specification of Letters Patent.

Patented Sept. 4, 1917.

Application filed March 23, 1916. Serial No. 86,295.

To all whom it may concern:

Be it known that I, HENRY H. VAUGHAN, of the city of Montreal, Province of Quebec, and Dominion of Canada, have invented 5 certain new and useful Improvements in Head-Gear; and I do hereby declare that the following is a full, clear, and exact description of the invention.

Heretofore there have been many attempts made to provide a head covering serviceable both in fair and stormy weather. In some cases ear coverings, such as ear muffs, for instance, detached from the head covering, have been used and in other cases 15 ear coverings have been attached and adapted to be turned up into the crown. In all cases, however, the head gear if affording protection for the ears lacked protection against rain or the water of melted snow 20 running from the crown of the cap over the ear covering and under the collar of the wearer.

The object of my invention is to provide a head covering with means whereby the 25 ears and back of the neck will be protected from both cold and rain or the water from melted snow lodging on the crown of the head gear; and to this end the invention may be said to consist of a combination with 30 the crown of the headgear of a horizontally extending rim and an ear covering member attached within the rear portion of the crown and adapted to be either turned down beneath the rim to protect the ears 35 and back of the neck, or turned upwardly into the crown when protection for the ears and neck is not required.

For full comprehension, however of my invention reference must be had to the accompanying drawings forming a part of 40 this specification, in which similar reference characters indicate the same parts, and wherein:

Figure 1 is a side elevation of my improved head gear arranged for inclement weather; and

Fig. 2 is a transverse sectional view thereof looking toward the rear.

I prefer to apply my invention to a hat, 50 and the crown thereof is indicated at B and the brim having its inner edge turned up within the crown at C, the sweat band stitched to the horizontal portion of the brim near the inner edge thereof and indicated at E, and the ear and neck protector

at D. I may construct the head gear of any of the materials at present employed for the purpose, the sweat band being of leather.

The ear and neck protector is cut to present rounded corners G of sufficient depth 60 to completely cover the ears and concaved upwardly at the rear as at H. This protector is secured to the hat by an attachment band K. One edge of the band is stitched to the horizontal brim C adjacent to the 65 stitching of the sweat band and the opposite edge is split and straddles the upper edge of the protector and the whole is secured together by a double line of stitching.

This particular manner of cutting the ear 70 and neck protector secures the co-action thereof with the usual coat collar when turned up, by fitting snugly just beneath the upper edge of and within the latter, thereby securing protection for the wearer 75 against both the wind and rain or snow while the rim effectively prevents the rain or water from melted snow from running down the back of the crown and onto the ear and neck protector and from it under 80 the collar of the wearer.

What I claim is as follows:

An article of headwear comprising a crown, a horizontal brim the inner edge of which is turned up within the crown, a 85 sweat-band stitched to the horizontal portion of the brim near the inner edge thereof, a unitary member adapted to be turned to different positions, in one position protecting the neck and ears of the wearer and 90 in the other position contained within the crown, the protecting member presenting rounded corners of sufficient depth to cover the ears of the wearer and having its lower edge upwardly concaved between the ear 95 portions to co-act with the coat collar, and an attachment band having one edge stitched to the horizontal portion of the brim over the sweat-band and having its opposite edge split and straddling one 100 edge of the protecting member and being stitched thereto.

In testimony whereof I have signed my name to this specification in the presence of two witnesses.

HENRY H. VAUGHAN.
